UNITED STATES PATENT OFFICE.

ALBERT BAUMGARTEN, OF FREEPORT, ILLINOIS.

DESIGN FOR A LEMON-SQUEEZER FRAME.

SPECIFICATION forming part of Design No. 31,934, dated December 5, 1899.

Application filed November 11, 1899. Serial No. 736,704. Term of patent 7 years.

To all whom it may concern:

Be it known that I, ALBERT BAUMGARTEN, a citizen of the United States of America, residing at Freeport, in the county of Stephenson and State of Illinois, have invented a certain new and original Design for Lemon-Squeezer Frames, of which the following is a specification.

My invention relates to a certain new and original design for lemon-squeezer frames.

The drawing shows the frame by means of a perspective view, said frame being composed of a central standard A, from the top and bottom of which extend upon one side diverging arms $a a' a^2 a^3$, the latter afterward converging at $a^4 a^5$. Upon the opposite side of the standard extends a leg B, terminating substantially in the plane of the diverging arms $a a'$, said leg being connected to the frame by

means of two portions $b b'$, extending, respectively, to the lower and upper portions of the standard.

The essential portion of the design is comprised in a frame having the central standard A, bearing divergent portions at the top and bottom upon one side and a leg extending from the other side and terminating substantially in the plane of the diverging portions at the bottom of the standard.

I claim as new and desire to secure by Letters Patent—

The design for a lemon-squeezer frame, herein shown and described.

ALBERT BAUMGARTEN.
